CLAIM

The ornamental design for an automotive diagnostic system, as shown and described.

DESCRIPTION

FIG. 1 is a perspective view of an automotive diagnostic system showing our new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view;

FIG. 8 is a perspective view;

FIG. 9 is a front elevational view;

FIG. 10 is a rear elevational view;

FIG. 11 is a left side elevational view;

FIG. 12 is a right side elevational view;

FIG. 13 is a top plan view; and,

FIG. 14 is a bottom plan view thereof.

FIGS. 1-7 have been drawn on a reduced scale with respect to FIGS. 8-15. Also, the broken line showing of a computer, a keyboard and printer are environmental only and form no part of the claimed design.
